UNITED STATES PATENT OFFICE.

MOLESWORTH KING, OF CHICAGO, ILLINOIS, ASSIGNOR OF ONE-HALF TO
LOUIS E. LAFLIN, OF SAME PLACE.

FIRE-PLACE.

SPECIFICATION forming part of Letters Patent No. 443,240, dated December 23, 1890.

Application filed May 21, 1890. Serial No. 352,623. (No model.)

To all whom it may concern:

Be it known that I, MOLESWORTH KING, of Chicago, in the county of Cook and State of Illinois, have invented a certain new and useful Improvement in Fire-Places; and I do hereby declare that the following is a full, clear, and complete description thereof, reference being had to the accompanying drawings, making a part of the same.

10 This invention is designed as an improvement on the improved fire-place patented to me November 3, 1885, by Letters Patent No. 329,747; and it consists in a double-set of dampers or one double damper to alternately cover one or the other of two openings and a supplemental damper in connection with the lower of said openings, which are made to operate together in a manner somewhat similar to that specified in said patent No. 329,747, 20 except that they are constructed differently and effect a different result, by means of which dampers a double draft is made, and the draft can be made more perfect, more easily controlled, and changed and regulated than by the means described in said patent.

In my application, Serial No. 352,622, filed herewith, I have claimed the triangular shield, hereinafter described, and shown in the drawings filed herewith, but to which I make no 30 claim in this application.

In the accompanying drawings, Figure 1 is a front view showing the dampers closed and the slide in the upper damper open. Fig. 2 is a sectional view showing all the dampers closed. Fig. 3 is a sectional view with the upper dampers open and one of the lower ones closed. Fig. 4 is a detail view of the two dampers made at right angles. Fig. 5 is a detail view of the shield.

40 A is the fire-place. B and C are the two openings in the rear of the inclined back b of the fire-place, as shown in Figs. 1, 2, and 3.

C² is a metallic shield made in a triangular shape with an opening D in its top and provided with a damper d', which is operated and regulated by the horizontal rod d. When the damper d' is closed in the top of this shield, it makes a perfect protection from falling soot and effectually closes up the opening of the flue.

b' and b³ are double dampers made rigid at right angles, so that when one is closed the other is always open, and are worked on pivots E E.

b⁵ are openings in the face of the damper b', and which are closed, when desired, by the slide b² by means of the eye b⁶.

b⁴ is the handle by means of which the double dampers b' and b³ are opened or closed. c is the lower damper pivoted at c² and is operated by means of the handle c'. These dampers b³, c, and d' can be operated by the use of a hooked poker. The damper c is provided with the nut c⁴ to prevent it from being closed tight, so that when drawn up to 65 close the opening C a space is always left open for the escape of gas.

d' is a damper in the top of the shield C², operated by the horizontal rod d when it is desired to close or regulate the opening D. 70

The operation of my invention is as follows: The result from the use of the two dampers b' and b³ when the slide in the damper b³ is closed is practically the same as that accomplished by the dampers in my said patent; 75 also, when the dampers b' and c are closed the result is the same as when the slide E is used in my said patent, effectually closing the rear part of the fire-place, except the opening made by means of the nut c⁴. But while my 80

said patent accomplishes all it was designed to do, yet there were defects in it which this invention was designed to cure. By the use of the upper damper d' in the top of the shield C² and the working of the lower damper 85 c on a pivot instead of as a slide and by placing the nut c⁴ so as to prevent being closed tight the gas from the coal can always escape and yet the heat be effectually retained when dampers c and b' are closed tight. In this 90

way the results of a base-burner stove are obtained, yet with the advantages of an open fire-place, and a perfect ventilation is had all the time. These advantages cannot be accomplished by my prior invention, as in that 95 one of the dampers is necessarily open when the fire is ignited, thus making too great a draft at all times for hard coal. When the fire is to be started, the lower dampers c and b³ and the damper d' in the top of the 100

shield are thrown open until the coal is sufficiently ignited. Either hard or soft coal can be used. When the damper b' is closed, damper b^3 is necessarily at right angles there-
 5 to and extends out toward the back of the shield, thus lessening the air-space in the shield, and thereby greatly increasing the draft, by means of which, together with the general construction of the other parts of my
 10 fire-place, there is no necessity of a blower when starting a fire or when shaking the ashes. After the coal is sufficiently ignited, damper d' in the top of the shield is regulated so as to have only sufficient draft as
 15 may be desired, damper b' is closed, and the slide b^2 therein left open or closed, as desired, and the damper c is lifted and drawn up, but by reason of the nut c^4 is not entirely closed. By this arrangement a fire can be made and
 20 regulated so as to utilize all the heat from the coal, and control it as the weather requires. The fire can be preserved as effectually as in a base-burner stove and yet give all the advantages of an open fire-place with complete
 25 ventilation.

The sides $a a$ are adjustable and can be adapted to any angle or raised or lowered, as desired.

The shield C^2 not only prevents dirt and
 30 soot from falling upon and clogging the dampers, but it protects the tile facing and mantels from excessive heat. It prevents a downward draft, and is a perfect prevention of smoke and ashes from coming in the room, and by
 35 the proper regulation of the dampers, a strong draft is created through the bottom dampers and the use of a blower entirely obviated. By the use of this shield much time is saved in setting, and it is practicable to set two
 40 open fire-places back to back, or one over the other, in the same flue, even if the flue is only eight inches by eight inches. The shield can also be used with a cook-stove in the same
 45 flue. This cannot be done with any other fire-place in use. Another advantage I claim

for my shield as constructed is that it can be set into any ordinary stove-flue or into any flue where the chimney is only built from the floor up, and it will save space occupied by a stove and can be set up with or without a 50 mantel.

This invention accomplishes all the results claimed by my prior invention, yet more effectually and in a different manner and by different means. All these advantages of 55 this improved fire-place have been demonstrated effectually and satisfactorily.

Now, having fully described my said invention, what I claim in this application is—

1. The combination, with a supporting- 60 damper plate having two orifices therein, of a double damper made rigid substantially at right angles, the same being pivoted to said supporting-plate midway between said orifices, whereby the tilting of said dampers 65 may close one orifice and open the other, substantially as shown.

2. A double damper consisting of two plates formed integral with and arranged at right angles to each other, having means for pivot- 70 ally attaching the same to a damper-plate, and openings in one of the plates of said damper, and a sliding plate having correspond- 75 ing openings therein, substantially as shown and described.

3. The combination, with a supporting- damper plate having double orifices therein, of a double rectangular-shaped damper piv- 80 otally mounted between said orifices, whereby one orifice may be opened and the other closed, and a supplemental damper in opera- 85 tive conjunction with the lowermost orifice, and means for preventing the same from entirely closing said orifice, substantially as shown and described.

MOLESWORTH KING.

In presence of—
 I. H. HIMES,
 LOUIS E. LAFLIN.
